JOSEPH O. MORRISON, OF ANDERSON, INDIANA.

MECHANICAL COUNTER.

1,203,644.

Specification of Letters Patent.

Patented Nov. 7, 1916.

Application filed April 17, 1912. Serial No. 691,284.

To all whom it may concern:

Be it known that I, JOSEPH O. MORRISON, a resident of Anderson, in the county of Madison and State of Indiana, (whose post-office address is Anderson, Indiana,) have invented certain new and useful Improvements in Mechanical Counters, of which the following is a specification.

This invention relates to mechanical counters, of the class wherein a plurality of mechanisms are provided to be successively and progressively actuated, the first being adapted to record the "units" quantities, and each succeeding mechanism being adapted, respectively, to record the respective next-succeeding higher-place quantities.

One of the objects of this invention is to provide means for "carrying-over" (i. e., actuating means to be interposed between one mechanism, when said mechanism has reached its individual limit of registration, and the succeeding mechanism) of an improved type. Another object is to provide means adapted to "clear" (i. e., adapted to actuate all the quantity-signaling elements to a zero registration), without causing said "clearing" means to be operated through a path of travel substantially greater in length than the full path normally traveled by one of said first-mentioned mechanisms.

Other objects of the invention, more or less broad than those stated above, together with the advantages inherent, will be in part obvious and in part specifically referred to in the course of the following description of the elements, combinations, arrangements of parts, and applications of principles constituting the invention; and the scope of protection contemplated will appear from the claims.

Referring now to the accompanying drawings, which are to be taken as a part of this specification, and wherein is illustrated one of the many possible embodiments of my invention; Figure 1 is a view in side elevation of said embodiment; Fig. 2 is a view in end elevation of the device illustrated in Fig. 1, after there have been removed nut 6, the washer 5, the actuating-handle 4, the screws 3, and the face-plate 2, and after having also removed from spindle 7 within casing 1 the spring-pawl carrier 18; Fig. 3 is a vertical sectional view taken longitudinally through said embodiment; Fig. 4 is a sectional view taken on the line $a-a$ of Fig. 3, looking in the direction of the arrow; Fig. 5 is a sec-

tional view taken on the line $b-b$ of Fig. 3, looking in the direction of the arrow; Fig. 6 is an illustration showing the rear-face of the ratchet wheel 9 illustrated in Fig. 2 and also of the rear-faces of certain other ratchet wheels hereinafter described; Fig. 7 is a side elevation of the ratchet-wheel illustrated in Fig. 6; Fig. 8 is a top plan view showing one of certain guiding rings 10, also shown in Figs. 1, 3, 4 and 5; Fig. 9 is a top plan view of one of the cams 15 hereinafter mentioned.

Similar reference characters refer to similar parts throughout the several views of the drawings.

Referring now particularly to the embodiment of this invention disclosed herein, 1 represents a casing, through which extends longitudinally as shown a spindle 7. At 75 one end thereof, outside the bottom wall of the said casing (said bottom being assumed to be the closed end wall), there is shown mounted on said spindle, between said spindle's cap 11 and the bossed portion formed 80 on the outside of said bottom wall of said casing 1, a "clearing" handle 12, provided with a pin 13 adapted to fit into a snap-pocket 14, thereby to hold said handle in its normal "ready-to-clear" and "post-cleared" 85 position. Starting from the left, in Fig. 3, there is shown within said casing 1 a cam 15 (keyed upon said spindle 7 as shown), a guiding ring 10 (fixed within said casing 1 as shown) and provided with an interior 90 notch as at 10', Fig. 8, and a ratchet wheel 9 (loosely mounted on said shaft 7 as shown). The rear-face of this bottom ratchet wheel is as illustrated in Figs. 6 and 7, in that it is provided on its under side 95 with a loosely mounted pawl 16, and in that it carries on its peripheral surface a zero-to-nine registration-series. Immediately over said bottom ratchet wheel 9, there are provided in the same order, and disposed in the 100 same respective relations, the elements of a second series of these parts, to wit, a cam 15, a guiding ring 10 and a ratchet wheel 9 (with its pawl 16 and its peripheral indicia as described above). Similarly, another set 105 of these parts is mounted over the set just-mentioned. Three of these sets have now been disclosed, and as each of them exposes through the window 17 in casing 1 (Fig. 1) a single digit, one in the "units" column, one 110 in the "tens" column and one in the "hundreds" column, it will be seen that the ca-

pacity of this embodiment is 999; for example, Fig. 1 discloses the suppositious total "576". Taking a section through the line *b*—*b* of Fig. 3, there is disclosed a relation 5 of the parts as illustrated in Fig. 5; where- in may be seen an observation window 17 (Fig. 1), a guiding ring 10, a spindle 7, a ratchet wheel 9 (loosely mounted on said spindle and disposed beneath said guiding 10 ring), and a cam 15 (fixedly keyed upon said spindle). There is also shown a pawl 16, carried on the rear face of the ratchet wheel thereabove, which latter is, as illustrated in Fig. 3, superposed over said cam; portions 15 of this last-named ratchet wheel being disclosed in section at A on Fig. 5.

With the above mentioned three sets of elements each set comprising in order a cam 15, a guiding ring 10, and a ratchet wheel 20 9 (see Fig. 5), superposed within casing 1 as illustrated in Fig. 3, a ratchet wheel 9, and the spindle 7, with the latter's key-way 25 7' (for keying cams 15 thereon—see Figs. 5 and 9); would be disclosed within casing 25 1 as illustrated in Fig. 2, were said casing to be viewed in plan from above its open end. Superposed over said exposed top ratchet wheel 9 (see Fig. 2), there is loosely mounted on said spindle 7 a pawl-and-spring 30 carrying-member 18, (see Fig. 4). This member 18 carries a pawl 19, adapted to coact with the teeth on the upper face of said ratchet wheel, and a leaf-spring 20, adapted to maintain said pawl in position 35 as shown. This member 18 is shown as being provided with a key-way 21 (Figs. 3 and 4), permitting, after face plate 2 has been screwed into position, actuating-handle 4 to be keyed, not upon said spindle, but 40 upon said member 18, as shown in Fig. 3. Washer 5 encircles spindle 7, and nut 6, threaded thereon, binds the parts together.

"Clearing" handle 12 carries thereon an operating knob 22, and the handle itself is 45 fixedly mounted upon said spindle 7 as illustrated in Figs. 1 and 3.

Having described this embodiment of this invention, the operation thereof may now be understood: The top ratchet wheel 9 50 illustrated in Fig. 2 necessarily having ten teeth as shown, as have the other ratchet wheels 9, it is clear that one complete revolution of this top ratchet wheel should, to bring about a successful operation of the 55 device, cause one-tenth of a revolution of the next succeeding ratchet wheel, and so on, from ratchet wheel to ratchet wheel, according to how many "columns" the capacity of the embodiment may be: and it is 60 clear also that this top ratchet wheel should move a one-tenth revolution to cause its peripherally-carried digit exposed through the window 17, Fig. 1, to be displaced by the digit one place higher. Now, upon giving 65 to member 18, through the suitable ac-

tuation of actuating handle 4, an operation in the direction of the arrow (Figs. 3 and 4) equal to one-tenth of a revolution, the top ratchet wheel 9 shown in Fig. 4 will also be given one-tenth of a revolution; and, assuming the indicating peripheral surfaces all initially registering zero through the window 17, the registered result will be "001." When in normal predetermined position, that is when it individually registers zero, this top ratchet 70 wheel 9 will be so disposed on guiding ring 10 (Fig. 5) that said ratchet wheel's underhung pawl 16 will not be in the effective position shown in full lines, (i. e., effective to engage the adjacent tooth of ratchet 75 wheel 9), but will occupy the position shown in dotted lines at 16' (i. e., swung clear, by means of the guiding action of ring 10, free of the tooth which would otherwise be there adjacent). Thereafter, when the top ratchet 80 wheel 9 is given successive fractional revolutions by the actuating means, this pawl 16, for nine of such fractional revolutions, is held free of engagement with a tooth upon the ratchet wheel 9 therebelow, due 85 to the control of lip 23, formed integrally upon the underside of said pawl (Fig. 7), which travels in the pathway between the interior irregular periphery of guiding ring 10 and the exterior irregular periphery of 90 cam 15 below said top ratchet wheel Figs. 3 and 5. When pawl 16 has been successively moved ten times from its dotted position 16' (Fig. 5), its next step travels in 95 said pathway, having again brought itself 100 within the notched or eccentric portion thereof of opposite the notch 10', will cause it to engage the next tooth upon the ratchet wheel next-below, and while simultaneously bringing its own ratchet wheel's visible registration again to "0," as predetermined, (said ratchet wheel having peripheral indicia as follows: 1 2 3 4 5 6 7 8 9 0), it gives the 105 next-below ratchet wheel a one-tenth revolution, thereby causing its visible registration to change from "0" to "1," so that the complete result will be as follows, "010." In this manner, by providing *x*-duplications of the cam-ring-ratchet-pawl combination, the registration may be made 110 to cover a total to *x* "places," for example, the present embodiment, comprising three of such combinations, covers a total to three "places," i. e., the total "999."

In order to "clear" the device, a very 120 simple operation is necessary. It should be understood that cams 15 are normally stationary, as illustrated in Fig. 5, since spindle 7 is normally stationary, the latter fact being due to the provision of pin 18 and its 125 registry with snap-pocket 14. It should be understood also that pawls 16 may be in different and varying positions in their respective paths of travel when it is desired to "clear" the device. It will therefore be 130

obvious that one complete actuation of "clearing-handle" 12, in a direction the reverse of that indicated by the arrow in Fig. 4, will cause said spindle 7 to carry all of 5 said cams 15 (which latter are as above described keyed on the former) so that each will sweep around the entire path of travel of its adjacent pawl, each thereby somewhere during its actuation abutting against 10 its said pawl and swinging the same back to the position illustrated in dotted lines in Fig. 5 and thereby causing a zero registration. To explain this resetting more in detail, say that the pawl 16 illustrated in 15 Fig. 5 is occupying another position, as the position 16', (to which, let us assume, it has been previously displaced during actuations of handle 4 in the direction of the arrow shown in Fig. 4), remembering as above 20 that the various other pawls 16 may be in different and varying positions in their respective paths of travel; wherefrom a description of the resetting operation of the cam 15 illustrated in Fig. 5, with reference 25 to the pawl 16 illustrated in said figure, may apply also to the similar and simultaneous operations of all the cams 15. Pawl 16, then, is at the position 16', its lip 23 (Figs. 5 and 6) being cleared, by means of 30 the interposed guiding ring 10, of engagement with all teeth carried by the ratchet wheel 9 therebelow except the tooth 10'. Now, when shaft 7 is as above turned in a direction the reverse of that indicated by 35 the arrow in Fig. 4, the cam 15 is turned with said shaft, whereby the curved nose 15' of the cam is caused to travel around in an anti-clockwise direction until finally it abuts against the wall 16'' of the lip 23 carried by the pawl 16 (it being still remembered that said pawl 16 is assumed to 40 be now occupying the position 16'). It is clear that said approach of cam 15 against the lip 23 has not at all been obstructed by 45 the existence of the pivot A, which pivot merely serves to mount the pawl 16 (illustrated in Fig. 5) upon a superposed ratchet wheel (not illustrated in Fig. 5). The further travel of nose 15' to complete its 50 return to the normal location illustrated, causes a similar return actuation of pawl 16 to its normal location in the shown latch-engagement with tooth 10' of the ratchet wheel therebelow, having, during such return actuation, been maintained away from 55 all other teeth of the ratchet-wheel last-mentioned by means of the guiding ring 10, and having been merely nosed past said tooth 10' by virtue of the usual ramp 10'' 60 carried by said notch as illustrated. And the return actuation of pawl 16 as just described, causing a return to zero registration (or normal location) of the ratchet wheel upon which said pawl is mounted 65 (said ratchet wheel, overlying the pawl 16,

obviously not being shown in Fig. 5); a similar and simultaneous return of the ratchet wheel below said pawl being accomplished by another pawl mounted on the rear of said ratchet wheel (said pawl not being shown in Fig. 5). Each ratchet wheel 9, as shown in Fig. 3, carrying a pawl 16 on the rear face thereof, and a cam 15 being mounted on shaft 7 in rear of each of said pawls, it will follow that a zero registration may thus be attained, no matter what the previous registration, by means of a single reserve revolution of shaft 7. In addition to attaining the ends and objects above referred to, it should be clear 80 that I have provided in this embodiment a device of a simple, compact and reliable nature, and one that is totally free, with but one exception, of any spring-means whatever. Obviously, too, this spring could 85 readily be eliminated.

As many changes could be made in the above construction and many apparently widely different embodiments of this invention could be made without departing from 90 the scope thereof, it is intended that all matter contained in the above description or shown in the accompanying drawing shall be interpreted as illustrative and not in a limiting sense. 95

It is also to be understood that the language used in the following claims is intended to cover all of the generic and specific features of the invention herein described and all statements of the scope of 100 the invention, which as a matter of language, might be said to fall therebetween.

Having described my invention, what I claim as new and desire to secure by Letters Patent, is:

1. In an apparatus of the class described, in combination, a revolute member normally occupying a predetermined position, operating means for moving the same in one direction, a second revolute member normally occupying a predetermined position, means controlled by said first mentioned revolute member and adapted to cause a fractional revolution of said second mentioned revolute member during each complete revolution of said first mentioned revolute member, transverse extensions on said revolute members, and means movable in the reverse direction adapted to engage said extension when the revolute members 115 are in other than their predetermined positions and thereby return both of said revolute members to their respective predetermined positions.

2. In an apparatus of the class described, 125 in combination, a revolute member normally occupying a predetermined position, operating means for moving the same in one direction, a second revolute member normally occupying a predetermined position, 130

means controlled by said first mentioned revoluble member and adapted to cause a fractional revolution of said second mentioned revoluble member during each complete revolution of said first mentioned revoluble member, transverse extensions on said revoluble members, and means movable in the reverse direction adapted to engage said extensions when the revoluble members are in abnormal position and thereby simultaneously return both of said revoluble members to their respective predetermined positions.

3. In an apparatus of the class described, in combination, a revoluble member normally occupying a predetermined position, operating means for moving the same in one direction, a second revoluble member normally occupying a predetermined position, means controlled by said first mentioned revoluble member and adapted to cause a fractional revolution of said second mentioned revoluble member during each complete revolution of said first mentioned revoluble member, transverse extensions on said revoluble members, a revoluble spindle upon which are loosely carried both of said revoluble members, means fixedly mounted on said spindle and adapted to engage the extensions when the revoluble members are in abnormal position and thereby return

both of said revoluble members to their respective predetermined positions upon the turning of said spindle in a reverse direction, and means to operate the spindle.

35

4. In an apparatus of the class described, in combination, a revoluble member, ratchet means comprising a plurality of ratchet units, said ratchet means controlling the revolution of said revoluble member, a fixed member provided with an opening, said opening being adapted to expose one of said units, a second revoluble member, operating means for causing a revolution of said second mentioned revoluble member, a pawl, normally occupying a predetermined position within said opening and adapted to travel within said opening and thereby to engage said exposed unit once during each revolution of said second mentioned revoluble member, an extension on said pawl, a revoluble spindle, and a member controlled by the revolution of said spindle adapted to engage the extension on said pawl and return the pawl to its normally predetermined position within said opening.

40

In witness whereof I have hereunto signed my name in the presence of two witnesses.

JOSEPH O. MORRISON.
